VALVE MEANS FOR USE IN QUENCHING INCANDESCENT COKE PRODUCED IN COKING CHAMBER OVENS

Wilhelm Salden, Essen, Heinrich Heine, Essen-Borbeck, and Erwin Sander, Essen-Werden, Germany, assignors, by mesne assignments, to Koppers Company, Inc., Pittsburgh, Pa., a corporation of Delaware

Application May 4, 1954, Serial No. 427,613

1 Claim. (Cl. 251—25)

The present invention is concerned with apparatus for quenching incandescent coke produced in coking chamber ovens or the type in which the quenching water for the coke is supplied to a quenching tower from an elevated container.

The coke produced in coking chamber ovens, after being gasified, is generally pushed from the oven chamber into a coke quenching car in which, after being transported from the oven chambers to a quenching tower arranged at one end of the oven battery, the coke is sprayed while in a hood under this tower with a voluminous quantity of water. In order to keep the consumption of quenching water down as much as possible the excess water is trapped after use and, after being clarified in a sump, is re-used. To this end the clarified quenching water is pumped again back to the elevated container arranged alongside the quenching tower and in due course is conducted from there back again to the spraying mechanism inside the tower for the next quenching operation.

It is essential in coke quenching, as is well known in this art, that the quantity of water which is required for coke quenching purposes shall be made available as rapidly as possible. It is even more important to stop the supply of coke quenching water instantaneously after quenching of the coke has been carried out, to avoid excessive absorption of water by the coke. The valves which have hitherto been arranged and devised for this special purpose in the discharge conduit leading from this elevated container to said hood are little suited to this purpose, more particularly because the small particles of coke which are still present in the clarified quenching water readily settle between the sealing surfaces of the valve and not only impair the fluid tight character thereof, but also produce heavy wear on the sealing surfaces. It is an object of the invention to provide for this purpose a quenching apparatus as described having a valve in the conduit from the elevated container to the spraying mechanism which will automatically open and close under the control of the water pressure in the container and without engendering substantial friction.

The invention resides in incorporating as the valve arranged in the discharge conduit from the elevated container a ball valve of such form and arrangement that it can be opened by the pressure of the water in the elevated container and against the pressure of liquid of said container disposed above the ball valve, and which otherwise acts on the ball valve holding it against its seat, through the agency of a diaphragm and a control conduit connected to the elevated container and provided with a control valve.

A quenching water valve of this nature in such system provides for an instantaneous opening of the valve as required for coke quenching merely by the opening of the control valve in the control conduit which leads from the elevated container to the diaphragm acting on the ball valve, so that the necessary coke quenching can commence immediately. Further, when the control valve in the control conduit is closed, the pressure of the con-

2

tents of the elevated container acts instantaneously on the ball element of the ball valve to produce an immediate closing of the latter. Thus opening and closing of the ball valve is carried out without substantial friction merely by the action of the pressure of the water in the elevated container as commonly stored alongside the hood for coke quenching.

In order, when it is required to allow the ball valve to close again, to get rid of the water which is present in the pressure chamber of the control valve beneath the diaphragm, in accordance with a further feature of the invention, the control valve takes the form of a three-way cock which is constructed and arranged so that the lower part of the pressure chamber is emptied on closure of the control valve and the diaphragm is allowed to return to its starting position.

Yet another feature of the invention resides in mounting the valve ball on one end of a lever arm on a pivot pin or spindle which passes laterally through the housing of the ball valve and which is connected outside the latter to the diaphragm through a suitable mechanical system. This avoids the necessity for having a valve rod connected to the diaphragm and passing vertically through the housing in a position in which it can only be held in sealed fashion with difficulty as a consequence of the contamination of the quenching water with particles of coke.

In accordance with a still further feature of the invention, in order to prevent the penetration of these contaminating coke particles into the mounting of the pivot pin or spindle of the mechanical system described above, and when this pivot pin is horizontally arranged, the pivot pin or spindle is preferably arranged to pass through a protuberance of the ball valve housing out of the main flow passage of the quenching water through the valve.

Another feature of the invention resides in arranging on the mechanical system comprising the pivot pin or spindle, an adjustable counter-weight adapted to take the closure pressure, the arrangement being such that this counterweight absorbs the sudden high pressure impulse from the head of water applied by the elevated container when the control valve in the control conduit is closed, thereby to protect, at least to a large extent, the valve body and the seating surface thereof against damage. In addition, the counterweight assists the lifting of the ball valve, and as a result it is further possible to make the thrust surface of the diaphragm, which is required for opening the valve, comparatively small, since by appropriate dimensioning of the counterweight the pressure acting on the diaphragm is only required to impart the necessary impulse to effect the opening. Furthermore, should the diaphragm assembly thereof fail, the counterweight enables the operation to be carried out directly by hand.

In accordance with yet another feature of the invention the valve ball is provided with a covering of resilient material, for example rubber, Buna, or one of the known plastics which are not sensitive to acids and are resistant to mechanical stress, so that a sealed closure is obtained even in the event of impurities lodging between the surfaces of the valve.

Finally it is a feature of the invention to make the diaphragm, which is used to open the ball valve, as a rigid plate with a bellows which is clamped at one end to this plate and at the other end to the ball valve housing. The bellows is of resilient material and substantially cylindrical in form, preferably being of the same material as the covering of the valve ball and particularly pliant and non-felting.

A preferred embodiment of the invention is illustrated

by way of example in the accompanying drawings in which:

Figure 1 is a diagrammatic illustration of quenching apparatus constructed in accordance with this invention,

Figure 2 is a vertical section through a valve as used in this assembly, and

Figure 3 is a plan view of the valve.

Referring first to Figure 1, a quenching car 1 loaded with incandescent coke pushed out of an oven chamber is shown located in the hood beneath the quenching tower 2 as conventional. Arranged in the hood of the quenching tower at a level to be above the quenching car when therein are spray conduits 3 which are fed through a pipe 4 from an elevated container or tank 5 alongside the tower 2. A valve 6 is incorporated in the pipe 4 and is controlled, by means of a diaphragm shown in Figure 2, from a control pipe 7 connected to the tank 5. The quenching water is supplied to the elevated tank by means of a pump 8, through a conduit 9 from a sump 10 which receives the water flowing away from the quenching car 1 during the quenching operation and which water has been clarified by weir separation of the coarse particles of coke decanted therefrom all as common in the art of coking.

As can be seen from Figure 2, the quenching water valve 6 comprises a housing 11 and a ball valve stopper element 12 which is applied, in the closed condition of the valve against an annular seating surface 13 of the valve housing by the pressure of the head of water in the container 5 at a level above the spray 3 and in the conduit 9 leading to this valve 6. The ball 12 is of metal and is covered with a resilient material, for example rubber, Buna, or a resistant plastic. The valve housing 11 is of a larger area than the ball in the region immediately above the ball 12, and is furnished with a limit seat 14 against which the ball bears when the valve is opened to enable the quenching water to discharge downwards through the open annular passage provided between the housing 11 and the lifted ball 12 when it is limited by the seat. The housing 11 is also provided internally with ribs 49 which form a guideway for the valve ball.

The valve housing 11 is made in two parts which are interconnected by flanges 15 and screws or the like, not shown on the drawing. The lower part of the valve housing 11 is in the form of a pipe bend. The valve ball bears loosely on a plate 41 connected to a fork 16, and a lever arm 18 is articulated by means of a bolt 17 between the forked arms 16. This lever arm 18 is disposed in a protuberance 19 of the housing 11 and is firmly secured to a pivot pin 20 passing through the walls of this protuberance, for example by a squared mounting thereon, the pin 20 being mounted in sealed fashion in a bushing 21 in the wall of the housing.

At its exit end the pin 20 is provided with a collar 22 which is disposed in a recessed bushing forming part of the wall of the housing and is pressed in sealed fashion against the base of this recess by means of a plug-form nut 23 having external screw threading. A rotatable lever 24 is rigidly connected to the pivot pin 20 at the end of the latter emerging from the wall of the protuberance 19 of the housing, and one arm of the lever 24 is articulated in the forked portion 25 of a rod 27 (Fig. 2) by means of a bolt 26, Fig. 3. This rod 27, which is vertically disposed, is firmly connected to a double-layer plate 29 by means of a nut 28, and is guided in an external bearing 30.

Clamped between the layers of plate 29 is the beaded inner periphery 31 of a substantially cylindrical bellows 32, the outer periphery 33 of the bellows being gripped between the flanges 34 of a casing secured to the underside of the valve housing 11 and defining a pressure chamber 35. This pressure chamber 35 is tapered at the bottom and is connected through a three-way cock 36 with the control conduit 7 leading to the elevated container 5. The upper part of the pressure chamber 35 above the plate 29 is open upwards, Fig. 3 and contains the valve

rod 27 which is merely guided by the eye bearing 30 on the housing.

Since the pressure of the head of water in tank 5 which acts downwards on the valve ball 12 is equal to the pressure which acts on the diaphragm 29, 32 when the three-way cock 36 is open, the effective pressure faces of the diaphragm 29, 32 is made larger than those of the valve ball 12 whereby to hold the valve 6 open under these conditions.

10 The other arm 37 of the lever 24 is furnished with an adjustable counterweight 38 which prevents the valve ball 12 from being impacted against its seat 13 by the sudden surge of water pressure resulting from the closing of the three-way cock 36. This substantially reduces the wear on the valve ball.

15 In addition, however, the use of the counterweight 38 has the advantage that it enables the thrust surfaces of the diaphragm 29, 32 to be kept relatively small, since this diaphragm is then merely used as a means of imparting an impulse for overcoming the pressure difference between the head of water on the upper part of ball 12 and the counterweight 38, acting on the valve ball from opposite side, not neglecting the friction. The diaphragm thus undergoes no expansion. The two-layer plate 29 rests on 20 projections 43 in the pressure chamber 35 when the valve is in the closed condition.

25 The quenching procedure is initiated by operation of the three-way cock 36 located in the control conduit 7, after the quenching car 1, with its charge of coke, is driven into the hood beneath the quenching tower 2. The quenching water flows through the control conduits 7 into the pressure chamber 35 and forces the plate 29, into the position shown by the right hand half of the diaphragm as it is illustrated in Figure 2, from the position illustrated in the left hand half of this figure, thereby to create an unbalance in the pressure applied to the ball valve 12 and shift it into its upper position against limit seat 14. As a result of the lifting of the ball valve 12, the quenching water is allowed to pass by gravity 30 through the pipe 4 into the spraying mechanism 3 until the tank 5 empties or the valve 6 is closed.

35 To close the valve 6 to terminate the quenching of the coke, the three-way cock is turned into its starting position to shut off the conduit 7, as a result of which the water under the diaphragm 29 can flow out of the pressure chamber 35. Under these conditions the pressure of the water in the tank 5 then acts only on the upper part of the valve ball 12 and the latter is therefore pressed against its seat 13.

40 The arrangement in accordance with the invention, while having been primarily devised for coke quenching, features thereof now also can be utilised for purposes other than the quenching of coke, in fact in all instances where it is desirable to make liquid quickly available 45 from an elevated container and to rapidly shut it off from the supply.

45 What we claim is:

50 Apparatus for making liquid quickly available from an elevated container and for rapidly shutting off the supply of liquid from the container comprising: a ball valve disposed in a gravity flow conduit leading from an elevated container, said valve comprising a freely floating ball in a chamber and a lower concave seat for the ball both under the hydrostatic head of the container upstream of the ball, a control conduit under the hydraulic 55 effect of liquid pressure in the container for exerting a thrust on the ball downstream thereof but in a direction upstream thereof, a diaphragm chamber connected to said control conduit with a diaphragm therein comprising a rigid central plate and a substantially cylindrical outer bellows surrounding the plate and clamped at its inner periphery to the periphery of the central plate and clamped at its outer periphery to the wall of the diaphragm chamber, for increasing the thrust of the hydraulic head in 60 the container to open the valve against the hydraulic

head of said container, a valve in said control conduit for supplying liquid to and exhausting liquid from said diaphragm chamber, a rotatable spindle disposed out of the path of the main flow of liquid through the valve, a ball lifting lever between the spindle and the ball, and a lever system comprising an adjustable counterweight system disposed at the exterior of the valve housing between the spindle and the diaphragm for regulating the opening movement of the ball by the spindle from the exterior of the valve housing.
